DESIGN FOR A GLIDER SUPPORTING FRAME

Milton B. Smith, Perrysburg, Ohio, assignor to
The Hettrick Manufacturing Company, Toledo,
Ohio, a corporation of Ohio

Application November 13, 1933. Serial No. 49,712

Term of patent 14 years

To all whom it may concern:

Be it known that I, MILTON B. SMITH, a citizen of the United States, and resident of Perrysburg, county of Wood, State of Ohio, have invented a new, original, and ornamental Design for a Glider Supporting Frame, of which the following is a specification, reference being had to the accompanying drawing forming a part thereof.

In the drawing,

Figure 1 is a perspective view of a glider supporting frame; and

Figure 2 is an end elevation of the glider supporting frame shown in Figure 1.

I claim:

The ornamental design for a glider supporting frame as shown.

In testimony whereof I have hereunto signed my name to this specification.

MILTON B. SMITH.
